UNITED STATES PATENT OFFICE.

WALLACE CHADWICK, OF SCHENECTADY, NEW YORK.

WRENCH.

1,169,007.

Specification of Letters Patent.

Patented Jan. 18, 1916.

Application filed October 31, 1914. Serial No. 869,627.

To all whom it may concern:

Be it known that I, WALLACE CHADWICK, a citizen of the United States, residing at Schenectady, in the county of Schenectady 5 and State of New York, have invented certain new and useful Improvements in Wrenches; and I do hereby declare the following to be a full, clear, and exact description of the invention, such as will enable 10 others skilled in the art to which it appertains to make and use the same.

This invention relates to new and useful improvements in wrenches, and has for its principal object to provide a wrench which 15 may be used as a substitute for the usual ratchet wrench.

Another object of the invention is to provide a wrench of the above character in which the necessity for using the usual pawl 20 and ratchet is eliminated.

A further object of the invention is to increase the gripping power of the wrench and provide a device which may be actuated from any angle.

With these and other objects in view, the invention consists in the novel combination and arrangement of parts which will be 25 fully set forth in the following specification and accompanying drawings, in which,

Figure 1 is a view partly in section of a wrench constructed in accordance with this invention, the handle partly broken away, Fig. 2 is a vertical sectional view taken on line 2—2 of Fig. 1, and showing the nut engaging member in full, Fig. 3 is a detail perspective view of one of the cover plates, and Fig. 4 is a view of the removable jaw.

Referring now to the drawings by characters of reference, the numeral 1 designates 40 the handle of the wrench provided at one end with the enlargement 2. This enlargement is provided with a central, circular aperture 3 in which the rotatable jaw member is mounted. A suitable recess 4 extends angularly into the portion 2 and communicates with the aperture 3 through the reduced bore 5. A suitable recess 6 is formed in the enlargement 2 in direct alinement with the central axis of the handle 1, and 45 the bottom wall of this recess is inclined as at 7 for a purpose which will be more fully hereinafter described. A suitable recess 8 extends in a plane parallel to the horizontal axis of the aperture 3 and is formed

in the enlargement 2 at a point so that it 55 comes intermediate the upper and lower terminals of one of the end walls of the recess 6. This recess 8 communicates with the recess 6 and is arranged to receive the mechanism which will be more fully hereinafter 60 described.

The rotatable jaw, which is designated by the numeral 9 comprises the circular body 10 having formed therein the peripheral groove 11, and this body is provided with the central hexagonal aperture 12 which is arranged to fit the nut upon which the device is used. The sides of the enlargement 2 surrounding the recess 6, are depressed as at 13 and arranged to receive the cover plates 14 which 70 are shaped to fit the depressions and curved as at 15 to conform to the contour of the aperture 3. A suitable screw-receiving aperture 16 is formed in each of the cover plates near one end and is arranged to receive the screw 17 which holds the plate in place. A suitable slot 18 is formed transversely of the plate near the opposite end and this slot is arranged to receive the trunnions of the roller which will be more fully 75 80 hereinafter described.

The roller above mentioned is arranged to rest in the recess 6 so that its periphery bears against the inclined wall 7 and the point diametrically opposite said wall is arranged to face the opening of the recess. A suitable retaining pin 19 is arranged to bear against the roller to force the same toward the reduced end of the recess and a suitable spring 20 is arranged to bear against the 85 head of the pin and the screw 21 to force the pin against and into engagement with the roller.

A suitable pin 22 extends through the aperture 5 and the head of said pin bears 95 against the spring 23, which spring is held in place in the recess 4 by means of the screw 24 and is designed to force the end of the pin inwardly and into the groove 11 to retain the jaw member 9 in place.

In order that the wrench may be made to fit nuts of different sizes, there are provided a plurality of removable jaw members 25 which comprise the bodies 26, which bodies are provided with the central recesses 27 in 105 which the nuts are arranged to rest. A suitable hexagonal extension 28 is formed on each body and is designed to fit within the

hexagonal recess 12 in the jaw member 9 so as to provide a wrench which is capable of being used for nuts of different sizes.

It will be apparent from the foregoing that in use when it is desired to tighten or loosen a nut, the wrench is placed in position according to the direction in which the nut is to be turned and upon pulling the handle in the proper direction it will be apparent that due to the inclined wall 7, the roller will engage the periphery of the jaw member 9 and thereby lock the same against movement in one direction. Upon twisting the handle in the opposite direction it will be apparent that the roller will disengage the periphery due to the inclination of the wall 7 and upon reversing the movement the gripping action will again take place, thus rotating the jaw member in but one direction. In this way it will be clearly seen that a particularly simple and efficient wrench is provided which will eliminate the necessity of using a pawl and a ratchet mechanism and the roller clutch is provided to effectively act as a substitute therefor.

While in the foregoing there has been shown and described the preferred embodiment of this invention, it is to be understood that such changes may be made in the

combination and arrangement of parts as will fall within the spirit and scope of the invention as defined in the appended claim.

What is claimed is:

A wrench comprising a handle, an enlargement formed on one end of said handle, 35 said enlargement provided with a central circular aperture therethrough, a recess formed in said handle and communicating with said opening, a jaw member rotatably mounted within the aperture of the handle, a roller 40 provided with trunnions on opposite sides thereof seated in said recess, a pair of cover plates for said recess and provided with elongated openings adapted to receive the trunnions of the roller, and means for holding the roller within the recess whereby upon movement in one direction of the handle, the roller will be wedged against the rear wall of the recess and against the movable jaw member and hold the same against further movement.

In testimony whereof I affix my signature in presence of two witnesses.

WALLACE CHADWICK.
